UNITED STATES PATENT OFFICE.

EBENEZER A. W. JEFFERIES, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

STEAM-BLOWER FOR GAS-PRODUCERS.

1,170,070.

Specification of Letters Patent.

Patented Feb. 1, 1916.

Application filed September 8, 1913. Serial No. 788,538.

To all whom it may concern:

Be it known that I, EBENEZER A. W. JEFFERIES, a citizen of the United States, residing at Worcester, in the county of Worcester and Commonwealth of Massachusetts, have invented a new and useful Improvement in Steam-Blowers for Gas-Producers, of which the following, together with the accompanying drawing, is a specification.

10 My invention relates to steam blowers for producing the blast necessary to support combustion within the combustion chamber of a gas producer, and more particularly to a form of steam blowers of this class having 15 a plurality of steam nozzles which coöperate to produce the blast.

In order that the gas producer may be operated efficiently, it is frequently necessary that the rate of combustion of the fuel 20 within the combustion chamber of the producer be such as to require a heavy blast of air or air and steam. It is common to produce the blast necessary to support combustion in a gas producer by means of a steam 25 blower having a single nozzle. There is a limit, however, to the size of such steam blowers beyond which they are not practicable, for the reason that an increase in the rate of flow of the steam does not cause 30 a corresponding increase in the rate at which the air is forced into the producer. When this limit has been reached, if the blast produced is not sufficient, it has been the practice to add one or more independent blowers to furnish the required additional blast. The provision of a plurality of independent 35 blowers, however, requires considerable valuable space beneath the base of the producer.

40 One of the objects of the invention, therefore, is to provide a form of steam blower the capacity of which may be increased practically indefinitely without impairing its efficiency, so that a heavy blast necessary to 45 support combustion in the largest gas producers may be supplied by a single steam blower.

Other objects and advantages will appear 50 from the following description taken in connection with the accompanying drawing, in which—

Figure 1 shows a sectional elevation of the lower portion of a gas producer equipped 55 with a multiple nozzle steam blower constructed in accordance with my invention;

Fig. 2 is a central longitudinal sectional view of the steam blower; and Fig. 3 is a sectional view of the steam blower on the line 3—3 of Fig. 2.

Like reference characters refer to similar parts in the different figures.

In the form of the invention shown in the drawing the blower includes a combining tube 1 leading to an upright pipe 2 which conducts the blast to the fuel within the fuel section 3 of the producer. The outer end of the combining tube 1 is cone shaped with its smaller end toward the producer. This cone shaped portion of the combining tube surrounds a plurality of steam nozzles 4, equally spaced about the axis of the combining tube. In the form of blower shown in the drawing, three equally spaced steam nozzles are used, although it will be obvious that a different number may be used if desired. The outer or larger end of the combining tube 1 is covered with a plate 5 having air admission openings 6, there being preferably one of said openings in line with each of the steam nozzles. This plate 5 has a central projection 7 extending into the combining tube and supporting the steam nozzles 4, as shown in Fig. 2. A space 8 within the projection 7 is joined by separate passages 9 to the various steam nozzles. Steam is conducted to the space 8 by a pipe 10 threaded axially into the plate 5, the steam passing from the space 8 through the separate passages 9 to the various nozzles. The three nozzles are supported by the projection 7 so that their axes converge slightly toward a common point. In front of each steam nozzle, and preferably slightly overlapping it, is a small tapered combining tube 11 and in front of each of these combining tubes 11, and preferably slightly overlapping it, is a second slightly larger combining tube 12. Each set of these small combining tubes 11 and 12 is formed integrally with a hub having an axial opening, the bolt 13 being passed through the openings in both hubs and being threaded into the projection 7 to secure the small combining tubes 11 and 12 in their proper positions. Relative rotation between the steam nozzles 4, the combining tubes 11 and the combining tubes 12 is prevented by small pins 14.

Pivoted to the pipe 10 and lying against the outer face of the plate 5 is a second plate 15. The plate 15 is provided with screened

openings 16 corresponding in number to the openings 6 in the plate 5. Rotation of the plate 15 about the pipe 10 carries the openings 16 into or out of register with the openings 6 so as to control the passage of air into the main combining tube 1. The plate 15 is pressed yieldingly against the plate 5 by a spring 17, the force of the spring 17 being determined by the position of the collar 18 upon the pipe 10. A lateral projection 19 at the periphery of the plate 15 overlaps the periphery of the fixed plate 5 and carries a set screw 20 adapted to engage the edge of the plate 5 and hold the plate 15 in any desired angular position.

In the operation of the blower, strong jets of steam pass from the nozzles 4 into the combining tubes 11, drawing air with them through these combining tubes. This air and steam then pass through the combining tubes 12, drawing in more air through the annular openings between the forward ends of the combining tubes 11 and the rear ends of the combining tubes 12. Air and steam then issue from the smaller ends of the combining tubes 12 and, after drawing still more air through the opening between these latter combining tubes and the main combining tube 1, pass through the inner and smaller portion of the main combining tube 1 and thence through the upright pipe 2 to the combustion chamber of the producer. By supporting the steam nozzles 4 and the combining tubes 11 and 12 upon the plate or cover 5 instead of upon the wall of the main combining tube 1, the passage of the air through the main combining tube 1 is interfered with as little as possible, this feature being important in its influence on the capacity of the blower.

While I have shown and described the details of one form of my invention, I do not wish to be limited to such details as changes may be made without departing from the spirit of the invention; but—

Having described my invention, what I claim as new and desire to secure by Letters Patent is:

1. In a steam blower for gas producers, a main combining tube, a plurality of steam nozzles within the main combining tube, a separate combining tube in front of each steam nozzle and within the main combining

tube, and means arranged axially within the main combining tube for supporting the nozzles and the combining tubes in front of the nozzles, said supporting means being itself supported at the rear of the nozzles.

2. In a steam blower for gas producers, a main combining tube, a cover for the outer end of the combining tube, a plurality of steam nozzles within the main combining tube, a separate combining tube in front of each steam nozzle and within the main combining tube, and means arranged axially within the main combining tube and supported by the central portion of said cover for supporting the nozzles and the combining tubes in front of the nozzles.

3. In a steam blower for gas producers, a main combining tube, a plurality of steam nozzles within the main combining tube, a support for the nozzles, a separate combining tube in front of each steam nozzle and within the main combining tube, the combining tubes in front of the nozzles being carried by a common hub, and means for securing the hub to the nozzle support.

4. In a steam blower for gas producers, a main combining tube, a cover for the main combining tube, said cover having air admission openings, a steam nozzle within the main combining tube, and a second combining tube in front of the steam nozzle and within the main combining tube, the steam nozzle and the second combining tube being supported by the cover of the main combining tube.

5. In a steam blower for gas producers, a main combining tube, a cover for the main combining tube, a steam nozzle within the main combining tube, a second combining tube in front of the steam nozzle and within the main combining tube, a pipe at the center of said cover to conduct steam to the steam nozzle, a plate pivoted upon the pipe and lying against the cover, the plate and cover having openings movable into and out of register by rotation of the plate, and means for pressing the plate yieldingly against the cover.

Dated this fifth day of September, 1913.

EBENEZER A. W. JEFFERIES.
